UNITED STATES PATENT OFFICE

OTHO M. OTTE, OF JAMESTOWN, NEW YORK.

BUFFER FOR DOORS.

1,149,078.

Specification of Letters Patent.

Patented Aug. 3, 1915.

Application filed April 17, 1914. Serial No. 832,414.

To all whom it may concern:

Be it known that I, OTHO M. OTTE, a citizen of the United States, residing at the city of Jamestown, in the county of Chautauqua and State of New York, have invented certain new and useful Improvements in Buffers for Doors, of which the following, taken in connection with the accompanying drawings, is a specification.

10 The invention relates to stopping or cushioning devices to prevent noise and shock resulting from the closing of doors and similar devices; and the object of the improvement is to provide a simple, cheap and durable construction which may be attached to doors and similar hinged devices and which serves the purpose without getting out of position or being otherwise impaired; and the invention consists in the novel features and combinations hereinafter set forth and claimed.

In the drawings, Figure 1 is a perspective view of a door and door frame with the door buffers in position on the door stop. Fig. 2 is an elevation of the corner of a door with a door stop inserted therein. Fig. 3 is a perspective view of a portion of a sheet metal door frame with the door stop attached thereto and a buffer for the door in said stop. Fig. 4 is a perspective view of the sheet metal spring holder for the door buffer; and Fig. 5 is a sectional view of the door stop or door with the sheet metal holder attached thereto and the door buffer therein.

Like numerals of reference refer to corresponding parts in the several views.

The numeral 10 designates a door, the numeral 11 the door frame, and the numeral 12 the door stop on said frame.

The buffer for the door 10 consists of a sheet metal spring holder 13 which is preferably made of sheet steel so as to give the proper resilience to said holder for the buffer block 17.

The holder strip 13 consists of the curved central portion 14 with the angular ends extending up to the lugs or flanged attach-

ing ends 15. The flanged ends 15 are attached to the inner surfaces of the door 50 stop 12 or door 10, preferably by spot welding, at each end of the opening 16 for the buffer block 17, which fits within the holder 13.

The buffer block 17 is preferably made of 55 cork, Mexican felt or linoleum, since these materials have a certain degree of resilience and are more durable than rubber, though rubber would serve a fair purpose in applicant's holder for a limited time. The 60 block 17 is formed with the notched ends 18 to receive the projecting ends 19 of the sheet metal door stop at each end of the opening 16. The block 17 may be inserted in one end and by bending the same for the 65 insertion of the opposite end so that it holds beneath the projecting plate 19 at each end. The block 17 projects beyond the outer surface of the plate 19 and will be held in the outwardly curved position shown in the 70 drawings as to its outer face. The edges of the strip 13 are preferably left disconnected with the adjacent walls of the door stop 12 and frame 11, so that said strip 13 may spring from the normal curved form 14 to 75 the straight lines shown in dotted line in Fig. 5, or any approach thereto necessary to stop the door 10. This simple arrangement forms a resilient stop of great durability and which can not get out of position. 80

I claim as new—

In combination with a hollow door stop, a buffer comprising a resilient sheet metal strip bent to provide flanges for attachment to the stop and a connecting back normally 85 curved forwardly and freely movable within said stop, and a buffer having its rear face engaged with said back, said back being flexed rearwardly upon impact of the door against the buffer. 90

In testimony whereof I have affixed my signature in the presence of two witnesses.

OTHO M. OTTE.
